UNITED STATES PATENT OFFICE.

HARRY LEIGH JOHNSTON, OF INDIANOLA, IOWA.

ANKLE BRACE.

Application filed October 29, 1926. Serial No. 144,963.

My invention is more particularly designed for use by athletes for the prevention of sprains or breaks in the wearer's ankle.

My object is to provide an ankle brace of this character of simple, durable and inexpensive construction, and so arranged that it will permit free and unhampered movement of the wearer's ankle to approximately the limit for which such movement is desirable when the wearer is engaged in athletic sports, but will form a positive stop to such movements beyond a point at which such movements can take place without danger of spraining or breaking the ankle.

15 My invention consists in the construction, arrangement and combination of the various parts of the device, whereby the objects contemplated are attained, as hereinafter more fully set forth, pointed out in my 20 claims, and illustrated in the accompanying drawings, in which:

Figure 1 is a side elevation of my improved ankle brace applied as in actual use.

Figure 2 shows a transverse, sectional 25 view through a portion of the shoe to which the brace is applied to illustrate the means for attaching the flexible limiting members to the shoe.

Referring to the accompanying drawings 30 I have used the reference numeral 10 to indicate an ankle strap which may be made of such material as leather, canvas or the like, and which is shaped to encircle the wearer's ankle above the ankle joint. I preferably 35 unite its ends adjustably by means of a lacing 11 so that it may be fitted snugly around the wearer's ankle. At the outer side of the ankle strap 10, I attach to the ankle strap a supporting strap 12 which extends upwardly 40 and around the inner side of the ankle strap and then downwardly to a point near the center of the ankle strap at the outer side thereof. The two ends of this strap 12 are provided with eyelets. These eyelets are 45 designed to adjustably and detachably receive flexible limiting wires or cords 13. In this connection I have successfully employed for these limiting devices small twisted wire cables, leather thongs and thick shoe strings.

50 For firmly anchoring the flexible limiting means to the sole of the shoe, I have provided between the layers of the sole of the shoe a series of rigid metal plates 14, their ends at the outer side of the shoe being 55 bent straight upwardly and formed with eyelets to receive the flexible limiting de-

vices. In the present instance I have illustrated three of these anchoring plates, the central one 14 being designed to receive a flexible limiting cord to extend straight upwardly and to be adjustably attached to the strap 10 at the central outer portion thereof. The two flexible limiting devices that are attached to the strap 12 are preferably crossed at their centers, as shown in the drawings, and this crossing preferably occurs just below the ankle joint.

In practical use, a shoe is first placed upon the wearer's foot and then the strap 10 is applied to the wearer's ankle above the 70 ankle joint and adjusted by means of the string 11 to snugly fit the wearer's ankle above the joint. Then the flexible limiting means are adjusted to such length that the wearer's ankle may have free and unlimited 75 movement to the extent necessary and desirable for effective athletic work, but the flexible limiting means are adjusted to such lengths that when the wearer's foot bends inwardly to a point beyond which it would be 80 dangerous to have it move, then the flexible limiting means are drawn taut and form a positive stop to such further movement, thus positively preventing sprains or breaks of the wearer's ankle caused by such inward 85 bending of the foot.

I have observed that in athletic games such as football a very large percentage of sprains and breaks occur on account of the inward bending of the foot beyond a certain 90 point, and for that reason I have especially designed my improved ankle brace with the object in view of positively limiting the amount of such inward movement beyond the danger point. I have, however, successfully 95 employed my improved ankle brace on the inner side of the wearer's ankle to limit the outward movement of the foot.

I claim as my invention:

1. An improved ankle brace, comprising 100 in combination a shoe, an ankle strap, means for adjustably securing it to a wearer's ankle above the ankle joint, and a limiting device attached to the ankle strap and to the sole of the shoe, and of such length that when 105 properly adjusted to the wearer's foot it will permit of a limited lateral tilting movement of the shoe sole and will limit said lateral tilting movement in one direction when it has passed beyond a certain predetermined 110 point, said limiting means being connected to the ankle strap and shoe in such positions

that when it is properly adjusted to fit the wearer's foot it will not interfere with the up and down movement of the wearer's foot about the ankle joint.

5. 2. An improved ankle brace, comprising in combination a shoe, an ankle strap designed to be adjustably secured to a wearer's ankle above the ankle joint, and a device for limiting the movement of the shoe sole relative to the wearer's ankle, said limiting device including a flexible substantially non-elastic member secured to the ankle strap in front of a vertical line through the ankle joint portion of the device and extended

downwardly and rearwardly and attached to the shoe sole at a point in the rear of a vertical line through the ankle joint of the device, and another member attached to the ankle strap in the rear of a vertical line through the ankle joint portion of the device and extended forwardly and downwardly and attached to the shoe sole at a point in front of a vertical line through the ankle joint portion of the device, substantially as and for the purposes stated.

25 Des Moines, Iowa, October 23, 1926.

HARRY LEIGH JOHNSTON.
